PERCUSSION FUSE

Marc Birkigt, Versoix, near Geneva, Switzerland

Application October 21, 1938, Serial No. 236,366
In Belgium January 21, 1938

9 Claims. (Cl. 102—39)

The present invention relates to percussion fuses for projectiles rotating about their axes, of the type in which the percussion system is temporarily locked in inoperative position by one or several pins adapted to be moved out of locking position, so as to release the percussion system, under the effect of the centrifugal acceleration resulting from the rotation of the projectile about its axis. The invention is more especially, although not exclusively, concerned with percussion fuses of this type for shells of small calibre.

In fuses of this type existing prior to my invention, the locking pins above referred to were driven off from the fuse body when the percussion system was released.

Now, the pins thus driven off from the body were moving at a very high speed, which involved very serious drawbacks, especially when the projectiles were utilized in firearms fitted on aircraft, since, in this case, said pins could damage certain vital parts of said aircraft.

The chief object of the present invention is to provide a fuse of the type above referred to which is better adapted to meet the requirements of practice and in particular which avoids the serious drawback above mentioned.

According to an essential feature of the present invention, the percussion fuse includes at least one pin adapted temporarily to lock the percussion system in inactive position, said pin being adapted to be moved out of locking position by the centrifugal acceleration resulting from the rotation of the projectile around its axis, and a recess is provided for receiving said pin, at the time of the release of the percussion system, so that it cannot be driven out of the fuse.

According to another feature of the present invention, the pin in question serves to lock a striker which, together with said pin, is carried by a movable support temporarily maintained in a position of rest for which said pin and its recess or housing are not located in register with each other, said support being adapted to occupy, under the influence of certain variations of the acceleration of the projectile along its trajectory, an active position for which said pin and said recess or housing are located opposite each other.

Other features of the present invention will result from the following detailed description of some specific embodiments thereof.

Preferred embodiments of the present invention will be hereinafter described, with refer-

ence to the accompanying drawing, given merely by way of example, and in which:

Fig. 1 is an axial sectional view of a percussion fuse made according to an embodiment of the invention;

Fig. 2 is a sectional view, corresponding to the same embodiment, but showing the parts in different respective positions.

In the following description, it will be assumed that the invention is applied to the production of a percussion fuse of the type above mentioned, for a shell of small caliber to be used in a firearm provided with rifling.

The general structure of the fuse, excepting the percussion means thereof, can be made of any suitable conventional manner, for instance as illustrated by the drawing.

In this embodiment, the fuse includes a body 1 on which is secured, by screwing, a cap 2, said body being adapted to fit into the mouth of the shell, through the medium of a threaded ring 3.

This body 1 carries a sheath 4 in which a detonator is housed, said sheath being secured by screwing to the base of ring 3.

A primer carrier 6 is provided with a flange 25 caught between the fuse body 1 and said sheath 4.

The front part of the fuse is closed by means of a thin sheet or disc 7, which is, for instance, caught, along its periphery, between the body 1 and the cap 2 of the fuse.

I will now describe the percussion system which constitutes the object of the invention.

Advantageously, this percussion system includes, in the known manner, a striker 8, normally kept in inactive position by pins 9 or equivalent means (two such pins being used in the embodiment shown by the drawing) adapted to be moved away radially, so as to release said striker, under the effect of the centrifugal acceleration resulting from the rotation of the projectile about its axis.

According to the chief feature of the present invention, the device is arranged in such manner that pins 9 can be driven off into recesses 10 capable of preventing them from being expelled from the body of the fuse.

Such an arrangement therefore obviates any risk of accidents such as those inherent in the operation of fuses having locking pins which are expelled from the fuse body.

Preferably, according to a further feature of the present invention, these recesses are wholly closed at their end farthest from the axis of the fuse. For instance, as shown by the drawing,

each of these recesses may be formed partly in the body 1 of the fuse and partly in its cap 2, by providing in these two last mentioned elements two radial holes, respectively, which open 5 into an axial hole 11 forming a housing for striker 8. Each of these radial recesses has a bottom 10' against which the corresponding locking pin 9 is applied when the striker is released.

With such an arrangement, I prevent the 10 possibility of destructive agents leaking in into the body of the fuse, and in particular the possibility of an inflow of water, which might damage the primer of said fuse.

A fuse as above described further includes 15 means for opposing premature release of striker 8, that is to say for preventing the fuse from acting at too short a distance from the gun muzzle.

Such means may be of any suitable type, but I 20 have found that, according to a feature of the present invention, which can be used separately, it is advantageous to make them as follows:

According to this feature, the striker 8 and its locking pins 9 are mounted on a support adapted 25 to slide in the bore 11 of the fuse body. Said support 12 is temporarily maintained in a position of rest for which said pins are located out of register with respect to the recesses 10 in which they are to engage, respectively. This support 30 12 is adapted to occupy, under the effect of certain variations of the acceleration of the projectile along its trajectory, an active position for which these pins are located opposite their respective recesses, so that they can now be moved 35 away radially under the effect of the centrifugal acceleration and release the striker.

Such an operation may, for instance, advantageously be obtained with the specific arrangement shown by the drawing.

40 In this embodiment, in order temporarily to maintain support 12 in its position of rest, I provide a locking means capable of releasing said support under the effect of the centrifugal acceleration. This locking means consists, for instance, of a split segment 13, interposed between the body 1 of the fuse and a shoulder 12' provided at the base of the sliding support 12.

45 The outer ends of pins 9 are made of frusto-conical shape so that they can already be partly engaged in recesses 10 when support 12 is in position of rest.

The forces acting upon support 12 after a shot has been fired, are then the following:

On the one hand, an axial force resulting from 55 the inertia of said support. The direction of this force changes at the same time as that of the acceleration of the projectile along its trajectory, that is to say after the projectile has left the firearm; and,

60 On the other hand, another axial force, directed toward the front end of the fuse, resulting from the reaction of the edges of recesses 10 upon the frusto-conical ends of pins 9, which are urged in the radial outward direction by the centrifugal 65 acceleration.

It will readily be understood that it is possible, by suitably choosing the weights of support 12 and pins 9, and also the angle of the cone of the latter, to obtain the result that the resultant 70 of these forces is directed toward the front end of the fuse, that is to say causes support 12 to pass from its position of rest to its active position, only after the projectile has moved to a given distance from the muzzle of the firearm. 75 This distance, added to that corresponding to the

axial change of position of support 12, determines the margin of safety.

In particular, in the case of shells of small calibre, it is particularly advantageous to determine the weights above referred to in such manner that this distance is equal to some meters. 5

The fuse above described will operate in the following manner:

In position of rest, that is to say before the projectile is introduced into the firearm, the various elements of the percussion system respectively occupy the positions of Fig. 1, support 12 being held in position of rest by segment 13.

When the shot is fired, the projectile starts rotating about its axis and said segment is moved 15 away by the centrifugal force, thus releasing support 12, which however remains for a short time in position of rest due to the fact that the acceleration of the projectile along its trajectory has an important positive value. When this 20 value drops below a certain value lower than that acting at the gun muzzle, said support comes into its active position and pins 9 are engaged into their recesses (position shown by Fig. 2). The fuse is now ready to operate. When the projectile strikes an obstacle, cover disc 1 is broken and striker 8 driven in. The point of this striker now strikes the fuse primer, so that said fuse now detonates.

Whatever be the embodiment that is chosen, 30 the fuse according to the present invention has, in addition to the advantages above set forth, that of being of a simple construction, so that its cost of manufacture is relatively low and its operation is reliable.

In a general manner, while I have, in the above description, disclosed what I deem to be practical and efficient embodiments of the present invention, it should be well understood that I do not wish to be limited thereto as there might be 40 changes made in the arrangement, disposition, and form of the parts without departing from the principle of the present invention as comprehended within the scope of the appended claims.

45 What I claim is:

1. A percussion fuse of the type described which comprises, in combination, a frame, a support movable axially in said frame between two extreme positions, a percussion device carried 50 by said support and movable axially with respect thereto, at least one locking member mounted in said support normally locking said percussion device against movement with respect to said support in an inoperative position, said locking member being movable radially away from the axis of the fuse by centrifugal force to release said percussion device, at least one hole in said frame, said hole being so located that said locking member is in register with said hole only 60 when said support reaches its extreme position nearest the front of the fuse, and locking means for temporarily locking said support in its other extreme position, said last means being brought out of action by centrifugal force only, whereby 65 said support can move towards the front of the fuse only after the shot is fired.

2. A percussion fuse of the type described which comprises, in combination, a frame, a support movable axially in said frame between two 70 extreme positions, a striker carried by said support and movable axially with respect thereto, at least one locking pin mounted in said support normally locking said striker against movement with respect to said support in an inoperative 75

position, said locking pin being movable radially away from the axis of the fuse by centrifugal force to release said striker, at least one hole in said frame, said hole being so located that said locking pin is in register with said hole only when said support reaches its extreme position nearest the front of the fuse, and locking means for temporarily locking said support in its other extreme position, said last means being brought out of action by centrifugal force only, whereby said support can be moved towards the front of the fuse only after the shot is fired.

3. A percussion fuse of the type described which comprises, in combination, a frame, a support movable axially in said frame between two extreme positions, a percussion device carried by said support and movable axially with respect thereto, at least one locking member mounted in said support normally locking said percussion device against movement with respect to said support in an inoperative position, said locking member being movable radially away from the axis of the fuse by centrifugal force to release said percussion device, at least one hole in said frame, said hole being so located that said locking member is in register with said hole only when said support reaches its extreme position nearest the front of the fuse, at least one abutment carried by said frame, at least one inclined surface on said locking member, said abutment and inclined surface cooperating to produce by the centrifugal force acting on said locking member a reaction parallel to the axis of the fuse tending to move said support towards its extreme position nearest the front of the fuse, and locking means for temporarily locking said support in its other extreme position, said means being brought out of action by centrifugal force only, whereby said support can be moved towards the front of the fuse only after the shot is fired.

4. A percussion fuse of the type described which comprises, in combination, a frame, a support movable axially in said frame between two extreme positions, a striker carried by said support and movable axially with respect thereto, at least one locking pin mounted in said support normally locking said striker against movement with respect to said support in an inoperative position, said locking member being movable radially away from the axis of the fuse by centrifugal force to release said striker, at least one hole in said frame, said hole being so located that said locking pin is in register with said hole only when said support reaches its extreme position nearest the front of the fuse, at least one in-

clined surface on said locking pin, at least one abutment carried by said frame, said abutment and inclined surface cooperating to produce by the centrifugal force acting on said locking pin a reaction parallel to the axis of the fuse tending to move said support towards its extreme position nearest the front of the fuse, and locking means for temporarily locking said support in its other extreme position, said means being brought out of action by centrifugal force only, whereby said support can be moved towards the front of the fuse only after the shot is fired.

5. A percussion fuse according to claim 2 in which the outer end of said pin is of frusto-conical shape, and said locking means normally lock said support in such an axial position that said frusto-conical end is engaged at an intermediate point along its conical surface with the edge of said hole, whereby the centrifugal force acting upon said pin after the fuse has started rotating about its axis tends by reaction on the edge of said hole of said frusto-conical end to urge said support towards the front of the fuse.

6. A percussion fuse according to claim 1 in which the locking means of the support comprise a split segment interposed between said support and said frame and capable of being forced open by centrifugal force.

7. A percussion fuse according to claim 2 in which the locking means of the support comprise a split segment interposed between said support and said frame and capable of being forced open by centrifugal force.

8. A percussion fuse according to claim 2 in which the locking means of the support comprise a split segment interposed between said support and said frame and capable of being forced open by centrifugal force and in which the outer end of said pin is of frusto-conical shape, and said locking means normally lock said support in such an axial position that said frusto-conical end is engaged at an intermediate point along its conical surface with the edge of said hole, whereby the centrifugal force acting upon said pin after the fuse has started rotating about its axis tends by reaction on the edge of said hole of said frusto-conical end to urge said support towards the front of the fuse.

9. In a percussion fuse according to claim 1, said frame having a recess therein, said support having a flange thereon within said recess, and said locking means comprising a split elastic ring normally positioned between said flange and the bottom of said recess.
